UNITED STATES PATENT OFFICE.

OTTO LINDEMANN, OF NEW YORK, N. Y.

DESIGN FOR A WING MEMBER FOR CLAMPING THE BASES OF BIRD-CAGES.

No. 39,995.

Specification for Design.

Patented May 18, 1909.

Application filed February 25, 1909. Serial No. 480,070. Term of patent 14 years.

To all whom it may concern:

Be it known that I, OTTO LINDEMANN, a citizen of the United States, residing at New York, in the county of Richmond and State of New York, have invented a new, original, and ornamental Design for a Wing Member for Clamping the Bases of Bird-Cages, of which the following is a specification, reference being had to the accompanying drawing, forming part thereof.

In this drawing Figure 1 shows a face view

of a wing member for clamping the base of bird cages, showing my new design. Fig. 2 shows an edge view of Fig. 1.

I claim:

The ornamental design for wing member for clamping the base of bird cages as shown.

OTTO LINDEMANN.
